The ornamental design for a paint pail, as shown and described.

DESCRIPTION

FIG. 1 is a perspective view showing my new design for a paint pail without the handle shown in FIG. 6;

FIG. 2 is a front elevation view thereof, the rear elevation view being the same;

FIG. 3 is a side elevation view thereof, the opposing side elevation view being the same;

FIG. 4 is a top plan view thereof;

FIG. 5 is a bottom plan view thereof;

FIG. 6 is a side elevation view with handle attached thereof;

FIG. 7 is a side elevation view of the handle portion of FIG. 5, the opposing side elevation view being the same;

FIG. 8 is a top plan view thereof;

FIG. 9 is a bottom plan view thereof; and,

FIG. 10 is an end elevation view thereof.

Broken lines in the drawings showing of the paint pail illustrate the parts of the paint pail that form no part of the claimed design.
